US0D1055164S

(12) **United States Design Patent** (10) **Patent No.:** **US D1,055,164 S**
(45) **Date of Patent:** **** Dec. 24, 2024**

(54) **GAMEPAD**

(71) Applicant: **HUBEI ZUANMA INTELLIGENT CONTROL TECHNOLOGY CO., LTD**, E'zhou (CN)

(72) Inventor: **Sen Wang**, Dongguan (CN)

(73) Assignee: **HUBEI ZUANMA INTELLIGENT CONTROL TECHNOLOGY CO., LTD**, E'zhou (CN)

(**) Term: **15 Years**

(21) Appl. No.: **29/959,426**

(22) Filed: **Aug. 26, 2024**

(51) LOC (14) Cl. **21-01**

(52) U.S. Cl.

USPC **D21/333**; D14/401; D14/218

(58) **Field of Classification Search**

(57) **CLAIM**

The ornamental design for a gamepad as shown and described.

DESCRIPTION

FIG. 1 is a perspective view of a gamepad showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the gamepad that form no part of the claimed design.

1 Claim, 8 Drawing Sheets
